(57) **CLAIM**

The ornamental design for an operating display panel, as shown and described.

DESCRIPTION

FIG. 1 is a top front perspective view of our new design for an operating display panel;

FIG. 2 is a front elevation view thereof;

FIG. 3 is a left elevation view thereof;

FIG. 4 is a rear elevation view thereof;

FIG. 5 is a top plan view thereof; and,

FIG. 6 is a bottom plan view thereof.

The broken lines showing particular elements of the operating display panel are included for illustrative purposes only and form no part of the claimed design.
